[57] CLAIM

The ornamental design for a tumbler or similar article, substantially as shown and described.

DESCRIPTION

FIG. 1 is a side elevational view of a tumbler or similar article showing my new design; the sides not shown are similar to the side shown;

FIG. 2 is a sectional view thereof, taken along the lines 2—2, as shown in FIG. 3, with the facets or design lines that would be seen from the interior having been omitted for clarity of illustration;

FIG. 3 is a top plan view thereof with the facets or design lines, as seen from the interior having been omitted for clarity of illustration;

FIG. 4 is a bottom plan view thereof; and

FIG. 5 is a sectional view thereof taken along the lines 5—5, looking in the direction of the arrows, as shown in FIG. 1.

FIG. 1
